ABSTRACT

A portable ball washer which includes a hollow, cylindrical body having closed top and bottom ends and a through aperture in its wall of substantially the same dimensions as those of a golf ball. The inside of the washer is coated with foam material which has good water-retention qualities, and the device is also provided with a ball-receiving means which consist of an elongate stem having a gripping handle on one end and a ball-receiving ring on the other. The ball-receiving means are reciprocal along the longitudinal axis of the body, so that the ring can be brought into registry with the aperture to receive the ball, following which the ball can be moved up and down in the body for washing purposes. The device also includes ways which engage portions of the ring to guide it during reciprocation of the ball-receiving means.

PORTABLE BALL WASHER

RELATED APPLICATIONS

None.

BACKGROUND OF THE INVENTION

This invention relates in general to devices for washing golf balls and, in particular, relates to a portable golf ball washer which can be carried with the player so that access to a washer is possible at all times, as contrasted to the presently existing, permanently located washers.

DESCRIPTION OF THE PRIOR ART

The following prior art is known to Applicant:

Meikle	U.S. Patent 2,023,932
Vandervort et al	U.S. Patent 2,822,558
Boynton	U.S. Patent 3,044,089
Derkocz	U.S. Patent 3,101,497
Frater	U.S. Patent 3,102,291
Thompson	U.S. Patent 3,271,802

While the above-noted art discloses various forms of ball washers, none of them possess the unique portability and simplicity of Applicant's washer. Furthermore, none of them utilize the foam or sponge-like material to both retain the soap and water solution as well as accomplish the scrubbing function.

SUMMARY OF THE INVENTION

It is common knowledge that golf balls will become soiled during play. Traditionally, ball washing devices have been situated adjacent the tee areas of golf courses, with these washers being permanently implaced and being available to the golfer only when he is in the tee area.

While these devices work relatively satisfactorily, a certain disadvantage is encountered because of the fact that they are only available to the golfer at certain fixed points on the golf course.

It is, therefore, felt advantageous to provide a portable washer which can be carried with the golfer and which is, therefore, available at any point on the course.

In conjunction with this, it has been found that by providing a relatively small, cylindrical container having closed top and bottom ends and a ball-receiving opening in the wall thereof, such a device can be readily carried with the golfer.

It has also been found that by lining the inside of the body with a foam or sponge-like material, only a minimum of water and soap solution is necessary to provide the necessary cleaning properties.

It has further been found that if a ball-receiving device including an elongate stem with a handle on its top end and a ring on its bottom end is provided, such a device may be reciprocated within the body so that the ring can be brought into registry with the aperture in the body to receive the ball, following which up and down movement of the ball-receiving means will effect a scrubbing action by the foam or sponge material on the ball.

It has also been found that a handle can be provided on the body of the washer so that it can be attached to a golf cart, golf bag, etc., and carried along with the golfer.

Finally, it has been discovered that by providing ways on the inside of the washer which contact part of the ring, the ring will travel in a fixed and pre-determined path when it is being reciprocated, and therefore no problem of registering the ring with the ball-receiving aperture will be encountered.

Accordingly, production of an improved portable ball washer of the type above-described becomes the principal object of this invention, with other objects thereof becoming more apparent upon a reading of the following brief specification considered and interpreted in view of the accompanying drawings.

OF THE DRAWINGS:

- FIG. 1 is a perspective view of the improved ball washer.
 FIG. 2 is a vertical section taken along the lines 2-2 of FIG. 1.
 FIG. 3 is a vertical section taken along the lines 3-3 of FIG. 2.
 FIG. 4 is a horizontal section taken along the lines 4-4 of FIG. 3.

DESCRIPTION OF THE PREFERRED EMBODIMENT

Considering first then FIG. 1, it will be noted that the ball washer, generally indicated by the numeral 10, consists of a hollow, cylindrical body 11 having top and bottom walls 12 and 13 to form a substantially closed chamber. A ball-receiving aperture 15 is disposed in the wall of the body 11 adjacent the top wall 12. The circumference or dimensions of this aperture will be slightly greater than those of the conventional golf ball.

The body 11 also carried a handle 14 which has two functions. First, this handle enables the user to grasp the washer with one hand while reciprocating the ball-receiving means, which will be described later, with the other. Second, the handle 14 makes it possible to support the washer on the golf bag or golf cart when not in use.

Considering next then FIGS. 2 and 3 in greater detail, it will be noted that the top wall 12 of body 11 has an upwardly projecting protuberance 12a and that a through bore 12b is formed therein.

The ball-receiving means include an elongate stem 21 which has a handle 20 on one end, which in the form of the invention shown in the drawings is in the form of a golf ball but which, of course, could take any desired configuration.

The opposed end of the stem 21 carries a ring 22, the circumference of which is sufficient to enable it to receive a golf ball.

The stem 21 freely slides in the bore 12b and, therefore, the entire ball-receiving means can be reciprocated along the longitudinal axis of the washer. The ring 22 can thus, of course, be brought into registry with aperture 15 to initially receive the ball B.

Considering next FIGS. 3 and 4, it will be noted that the interior of the body 11 is lined with substantially semi-circular foam or sponge members 16,16. These members are bonded or secured to the inside of body 11 in any suitable fashion, and one of their chief advantages is that they have high moisture retention properties. Also disposed within the body 11 are opposed ways 17,17 and 18,18 formed of strips of fairly rigid material which will engage part of the periphery of the ring 22, as clearly shown in FIG. 4, to ensure straight-line movement and also to ensure that when the ring is pulled to its topmost position, it will be in alignment with the aperture 15.

In use or operation of the improved ball washer, it will first be assumed that a limited amount of water and soap in solution has been placed in the washer to impregnate the sponge or foam material 16,16.

At that point and when it is desired to clean a ball, it is merely necessary to pull the handle 20 up, resulting in registry of the ring 22 with the aperture 15. At that time the golf ball is inserted through the aperture, and the handle 20 is pumped up and down. At this point, and as clearly shown in FIG. 3, the ball B will be in contact with the foam or sponge material 16,16 to permit the necessary cleaning operation.

The ways 17,17 and 18,18 ensure that the ring 22 will travel in a straight-lined path or movement, therefore ensuring that it will always be capable of being brought back into registry with the aperture 15 to remove the ball B.

It has, therefore, been shown how a relatively simple, unique, and inexpensive portable ball washer has been disclosed.

It should be noted here that while some sort of plastic material might be suitable for the various components, the device is not intended to be limited to any particular material.

While a full and complete description of the invention has been set forth in accordance with the dictates of the Patent Statutes, it should be understood that modifications can be resorted to without departing from the spirit hereof or the scope of the appended claims.

What is claimed is:

1. A portable ball washer, comprising:
  - A. a hollow substantially cylindrical body with
    1. an apertured top wall and an opposed bottom wall;
  - B. substantially semi-circular opposed moisture retention means of absorbent foam material lining the interior walls of said body throughout its length;
  - C. said walls of said body and said moisture retention means having at least one ball-receiving aperture therein;
  - D. ball-receiving means including

5

15

1. an elongate stem slidably received in said aperture of said top wall and
2. a handle mounted on one end of said stem and
3. a ball-receiving ring mounted on the opposed end of said stem; and
- E. spaced opposed rails
  1. extending the length of said body and
  2. spacing said opposed moisture retention means from each other and
  3. coacting with said ring to control the path of movement of said ball-receiving means.
2. The device of claim 1 further characterized by the presence of a carrying handle secured to said body.
